(57) **CLAIM**

The ornamental design for a dispenser, as shown and described.

DESCRIPTION

FIG. 1 is a front perspective view of a dispenser showing my new design;

FIG. 2 is an enlarged front perspective view of the drain portion of the dispenser broken away for ease of illustration;

FIG. 3 is a front view of the dispenser;

FIG. 4 is a rear view of the dispenser;

FIG. 5 is a left side view of the dispenser, the right side view is a mirror image of the left side view;

FIG. 6 is a top view of the dispenser; and,

FIG. 7 is a bottom view of the dispenser.

The broken lines are for illustrative purposes only and form no part of the claimed design.

1 Claim, 6 Drawing Sheets
